UNITED STATES PATENT OFFICE.

CLARENCE W. FREY, OF ENDICOTT, NEW YORK, ASSIGNOR TO ENDICOTT JOHNSON CORPORATION, OF ENDICOTT, NEW YORK, A CORPORATION OF NEW YORK.

DESIGN FOR A SOLE FOR BOOTS AND SHOES.

Application filed July 10, 1928. Serial No 27,439. Term of patent 14 years.

To all whom it may concern:

Be it known that I, CLARENCE W. FREY, a citizen of the United States, residing at Endicott, in the county of Broome, and State of New York, have invented a new, original, and ornamental Design for a Sole for Boots and Shoes, as shown in the accompanying drawing, forming a part of this specification.

In said drawing:—

Fig. 1 is a plan view of the sole.

Fig. 2 is an enlarged section therethrough on the line 2—2 Fig. 1.

I claim:

The ornamental design for a sole for boots and shoes, substantially as shown.

CLARENCE W. FREY.
